UNITED STATES PATENT OFFICE.

CARL HEIRICH, OF COLOGNE, GERMANY.

HYDRAULIC AIR-COMPRESSOR.

1,057,961.

Specification of Letters Patent.

Patented Apr. 1, 1913.

Application filed February 9, 1912. Serial No. 676,578.

To all whom it may concern:

Be it known that I, CARL HEIRICH, a subject of the King of Prussia, residing at 35 Ubierring, Cologne-on-the-Rhine, Germany, have invented certain new and useful Improvements in Hydraulic Air-Compressors; and I do hereby declare the following to be a full, clear, and exact description of the invention.

10 My invention relates to hydraulic air-compressors.

One illustrative embodiment of my invention is represented by way of example in the accompanying drawing, wherein:—

15 Figure 1 is a vertical section showing a well-known hydraulic air-compressor and Fig. 2 is a like view showing an improved hydraulic air-compressor according to my invention.

20 Referring firstly to Fig. 1, in the hydraulic air-compressors constructed heretofore according to Taylor's system on the principle of the water-drum blower, the water flowing into the head-race W de-

25 scends in a vertical descending-pipe F, while at its upper end it sucks air through the inlets B and carries it along into a chamber A at the bottom of the said pipe where the air is separated and collected in consequence

30 of the enlargement of the cross-section, while the water liberated from air flows laterally, rises in the shaft and flows away at C. The separated compressed air is removed from the chamber through a separate

35 ascending pipe L. In the hydraulic compressors heretofore constructed according to Taylor's system both the descending pipe and the chamber are made of sheet iron. The assembling and construction of this

40 iron apparatus in the shaft and underground chamber is a difficult and expensive matter. Also, as the apparatus can be erected only in the shaft and chamber when they are free from water, either the water

45 must be constantly pumped away or tubing is necessary, so that in districts which abound in water or are flooded such great expense is entailed that the construction of the apparatus is out of the question. If it

50 is desired, however, to make the narrow shaft requisite for containing both the descending-pipe and the rising water of the same dimensions as the underground chamber requisite for containing the separating

55 and storage chamber in order to be able to assemble the entire apparatus above ground

and to lower it under water, this would be impossible in practice in the case of relatively small plants in consequence of the enormous excavating costs alone, as indicated by dotted lines in Fig. 1. In contradistinction thereto, according to my invention, I make the separating and storage chamber and, under certain circumstances, the descending-pipe also, of a flexible material, e. g. rubber-coated fabric, so that the entire apparatus can be completely assembled above ground, then lowered through the narrow shaft in a folded or rolled condition, and finally expanded or inflated in 60 a suitable manner. As this lowering and expansion or inflation can take place without any difficulty under water, when the apparatus according to my invention is employed it is not necessary to pump out the 65 water or to provide tubing and consequently my apparatus can be used even in very wet or flooded ground. Further, the employment of the specifically light and elastic material enables hydraulic compressors or accumulators to be sunk and anchored in the sea, which is impossible when heavy rigid sheet iron constructions are employed owing to the motion of the waves.

70 In Fig. 2, showing a plant according to 85 my invention by way of example, similar reference numerals designate similar parts, the material difference being that either the chamber A alone, or both the chamber A and the pipe F, is or are made of a flexible 90 material, e. g. rubber-coated fabric. Otherwise, the arrangement and mode of operation of the apparatus are substantially the same as described above with reference to Fig. 1.

95 I claim:—

1. In a hydraulic air-compressor of the type described, the combination, with a descending-pipe, of a separating and storage chamber connected therewith and composed 100 of a flexible material, and an ascending-pipe connected with the said chamber.

2. In a hydraulic air-compressor of the type described, the combination of a descending-pipe, a separating and storage 105 chamber connected therewith, and an ascending-pipe connected with the said chamber, the said descending-pipe and the said chamber being composed of a flexible foldable material, for the purpose specified.

110 3. In a hydraulic air compressor of the type described, a water receiving device, a

descending pipe designed to receive water from said water receiving device, and a water ascending pipe surrounding said descending pipe for part of its distance, a 5 separating and storage chamber formed of flexible material connected with said descending pipe, and means for guiding air from said separating and storage chamber.

4. In a hydraulic air compressor of the 10 type described, a water receiving housing, a descending pipe formed with a head having apertures communicating with the air and with said water receiving housing whereby air and water are caused to move 15 downward through said descending pipe, a flexible pipe surrounding said descending pipe for part of its distance, a collapsible separating and storage chamber connected with said flexible pipe, and means for guiding 20 the air from said separating and storage chamber.

5. In a hydraulic air compressor of the type described, a descending pipe of rigid material formed with a head having an air 25 receiving aperture and a water receiving aperture, a water receiving housing surrounding said head and adapted to guide water into said water receiving aperture

whereby air and water are forced down 30 said descending pipe, an ascending pipe surrounding said descending pipe for part of its distance, and a foldable flexible separating 35 and storage chamber connected with said descending pipe in such a manner as to cause the descending pipe to project to a point below the top of said chamber, and means for guiding air from the top of said chamber to a point of discharge.

6. In a hydraulic air compressor, the combination of a descending pipe for conveying 40 downwardly a mixture of air and water, a separating and storage chamber connected with said descending pipe and made compressible so as to be easily inserted through an opening of smaller diameter than the 45 normal external diameter of said chamber, means for discharging water from said chamber, and means for conveying air from said chamber.

In testimony whereof I have signed my 50 name to this specification, in the presence of two subscribing witnesses.

CARL HEIRICH.
